UNITED STATES PATENT OFFICE.

GRIFFITH H. CLOVER, OF CHICAGO, ILLINOIS, ASSIGNOR OF ONE-HALF TO
JOHN J. BECKER, OF CHICAGO, ILLINOIS.

CUT-OFF-VALVE CONTROLLER.

SPECIFICATION forming part of Letters Patent No. 717,812, dated January 6, 1903.

Application filed February 18, 1902. Serial No. 94,587. (No model.)

To all whom it may concern:

Be it known that I, GRIFFITH H. CLOVER, a citizen of the United States, and a resident of Chicago, in the county of Cook and State of Illinois, have invented a new and Improved Cut-Off-Valve Controller, of which the following is a full, clear, and exact description.

The invention relates to compound steam-engines; and its object is to provide a new and improved cut-off-valve controller arranged to govern the cut-off valve of the low-pressure cylinder according to the load, so that the engine runs with great regularity and without shock or jar, the controller being simple and durable in construction, readily applied to the engine, and not liable to get out of order.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement as applied to the trip-collar of a Corliss compound engine. Fig. 2 is an edge view of the cut-off indicator to show the amount of the cut-off of the valve; and Fig. 3, represents a side elevation of the high and low pressure cylinders, the receiver, and valve-gear connections of a Corliss engine with the improvement connected thereto.

In the drawings, 1 represents the high-pressure cylinder of a Corliss engine; 2, the low-pressure cylinder, each being provided with valve-gear and connections of the usual kind, and 3 represents the receiver connected by pipes with the high and low pressure cylinders.

The trip-collar A of the cut-off valve of an engine of this type is provided on one side with an arm B, pivotally connected by a link C with one end of a lever D, carrying at its other end an adjustable weight D', the said lever being fulcrumed at or near its middle on a link E, held on a bracket E', attached to the pressure-cylinder F, held on a support G,

carried by a post G', attached to the base of the engine or other suitable part thereof. In the pressure-cylinder F reciprocates a piston H, connected by its piston-rod H' with the lever D on the side carrying the weight D', as plainly shown in Fig. 1, so that the weighted lever imparts a down or return movement to the piston H, as hereinafter more fully described.

The pressure-cylinder F is connected at its lower end by a pipe I, having a valve I', with the receiver of the engine, so that the steam passes through the pipe I into the lower end of the cylinder F to act against the bottom of the piston H, so as to move the same upward against the weighted lever D to impart a swinging motion to the same and to consequently turn the trip-collar A to reduce the cut-off of the cut-off valve. When the steam-pressure becomes less in the cylinder F, then the weighted lever D forces the piston H to move downward, whereby the trip-collar A is turned in an opposite direction to enlarge the cut-off of the valve, and thereby admit more steam to the cylinder. The upper end of the cylinder F is provided with a drip-pipe J, open to the atmosphere. Now in order to insure a gradual up-and-down swinging movement of the lever D and a consequent easy turning of the trip-collar A in either direction to avoid all shock or jar, I connect the end of the lever D adjacent to the link C with the piston-rod K' of the piston K, reciprocating in a cushioning-cylinder L, pivotally connected at its bottom by a projection L' with the support G. A by-pass N connects the ends of the cushioning-cylinder L with each other, and in the said by-pass is arranged a valve N' under the control of the operator to regulate the flow of the fluid in the cylinder L from one end to the other. The cylinder L is preferably filled with oil, glycerin, or the like fluid to give the desired resistance to the piston K in both its up and down movement, it being understood that this can be increased or diminished by adjusting the valve N' so as to allow more or less of the fluid to pass from one end of the cylinder to the other within a given time.

The lever D is fulcrumed on the link E and the cylinder L is fulcrumed on the support G,

so as to allow the piston-rods H' and K', connected with the lever D, to have free and easy movement without danger of binding in their bearings. The cut-off-valve controller above 5 described by regulating the cut-off controls the receiver-pressure and causes it to remain constant.

In order to indicate the amount of the cut-off of the valve, I provide the trip-collar A 10 with a graduation, (see Fig. 2,) on which indicates a pointer P, fixed to a stationary support, such as the bonnet A' of the cut-off valve. Now it will be seen that when the trip-collar A is turned the pointer indicates 15 on the graduation O the amount of the cut-off. As shown in the drawings, the indicator is in the form of a curved graduated plate secured to the periphery of the trip-collar and from which the arm B extends.

20 I do not limit myself to the particular application of the improvement to the low-pressure cylinder of a Corliss engine, as the device may be used for other purposes without deviating from the spirit of my invention.

25 Having thus described my invention, I claim as new and desire to secure by Letters Patent—

1. The combination with an engine having a high and low pressure cylinder, a receiver 30 and valve-gear, of a controller having a weighted lever operatively connected with the device consisting of a fluid-containing cylinder and a piston in said cylinder and cut-off valve of the low-pressure cylinder, a cushioning device connected with one end of the 35 said lever, and an actuating device connected with the weighted end of the said lever, the actuating device comprising a pressure-cylinder connected with the receiver, and a piston 40 ton in the said pressure-cylinder and connected with the weighted end of the lever, as set forth.

2. The combination with the engine-cylinder, and the cut-off valve, of controller comprising a pressure-cylinder, connected at one 45 end with a pressure-supply, a piston moving in the said cylinder, a lever connected with the piston-rod of the said piston and carrying a weight to govern the return movement 50 of the said piston, the said lever being operatively connected with the cut-off valve, a cushioning-cylinder pivoted at its lower end and having a valve-controlled by-pass to connect its ends with each other, the cushioning-cylinder being filled with a fluid, and a piston 55 in the said cushioning-cylinder and connected with the said lever, as set forth.

3. In a compound engine, the combination 60 with the low-pressure cylinder, and a cut-off valve having a trip-collar provided with an arm extending therefrom, of a cut-off-valve controller, comprising a pressure-cylinder connected with a fluid-pressure supply, a piston movable in the said cylinder in one direction, 65 by the fluid passing into the cylinder, a lever carrying a weight and connected at its weighted end with the said piston, the weighted lever

imparting a return movement to the said piston, a link connecting the other end of the lever with the arm on the trip-collar of the 70 cut-off valve, a cushioning device connected with this end of the lever and comprising a cylinder having a valved by-pass connecting the ends of the cylinder with each other, the cylinder being filled with a fluid, and a piston in this cushioning-cylinder and connected with the said lever, as set forth.

4. The combination with an engine-cylinder, and a cut-off valve having a trip-collar, 80 of a curved graduated plate secured on said trip-collar, and a fixed pointer indicating on the said graduation the amount of the cut-off of the valve.

5. The combination with an engine-cylinder, and a cut-off valve having a trip-collar, 85 of a graduated plate secured on the trip-collar, an arm extending from said plate, a fixed pointer on the bonnet of the cut-off valve, and a controlling device for governing the cut-off valve and connected with the said 90 arm, as set forth.

6. The combination with an engine having a high and low pressure cylinder, a receiver, and valve-gear, of a controller for governing the cut-off valve of the low pressure cylinder, 95 the said controller comprising a weighted lever connected with the trip-collar of the cut-off valve, a cushioning device consisting of a fluid-containing cylinder and a piston in said cylinder and connected with one end of 100 said lever, a pressure-cylinder connected with the receiver, a piston in said pressure-cylinder and connected with the other, or weighted end of said lever, as set forth.

7. The combination with an engine having 105 a high and low pressure cylinder, a receiver and valve-gear, of a controller for governing the cut-off valve of the low-pressure cylinder, the said controller comprising a pressure-cylinder connected at one end with the receiver, 110 a piston moving in the said cylinder, a lever connected at one side of its fulcrum with the piston-rod of the said piston and carrying a weight to govern the return movement of the 115 said piston, a link connecting one end of said lever with the trip-collar of the cut-off valve, a cushioning-cylinder having a by-pass to connect its ends with each other, the cushioning-cylinder being filled with a fluid, and a piston in the said cushioning-cylinder and 120 connected with the said lever at the other side of its fulcrum, as set forth.

8. The combination with a compound engine having a high and low pressure cylinder, 125 a receiver and valve-gear, of a controller for governing the cut-off valve of the low-pressure cylinder, the said controller comprising a pressure-cylinder connected by a valve-controlled pipe with the receiver and provided with a drip-pipe at its upper end open to the 130 atmosphere, a piston movable in the said cylinder in one direction by the fluid passing into the cylinder, a lever carrying a weight at one end and connected at its weighted end

with the said piston, the weighted lever imparting a return movement to the said piston, a link connecting the other end of said lever with the trip-collar of the cut-off valve, a cushioning device connected with this end of the lever and comprising a cylinder, having a valved by-pass connecting the ends of the cylinder with each other, the cylinder being filled with a fluid, and a piston in the cushioning device connected with the said lever, as set forth.

In testimony whereof I have signed my name to this specification in the presence of two subscribing witnesses.
